CLAIM

The ornamental design for a housing for a display telephone unit, as shown and described.

DESCRIPTION

FIG. 1 is a top, front, and right side perspective view of a housing for a display telephone unit showing the display elevated and rotated to face frontwards;

FIG. 2 is a front elevational view of the housing for a display telephone unit showing the display elevated and rotated to face frontwards;

FIG. 3 is a rear elevational view of the housing for a display telephone unit showing the display elevated and rotated to face frontwards;

FIG. 4 is a right side elevational view of the housing for a display telephone unit showing the display elevated and rotated to face frontwards;

FIG. 5 is a left side elevational view of the housing for a display telephone unit showing the display elevated and rotated to face frontwards;

FIG. 6 is a top plan view of the housing for a display telephone unit showing the display elevated and rotated to face frontwards; and,

FIG. 7 is a bottom plan view of the housing for a display telephone unit showing the display elevated and rotated to face frontwards.

The broken line showings throughout the views are for illustrative purposes only and form no part of the claimed design.
